[57] CLAIM

The ornamental design for a housing portion for a hand-held computer, as shown and described.

DESCRIPTION

FIG. 1 is a bottom front isometric view of a housing portion for a hand-held computer showing our new design;

FIG. 2 is a top rear isometric view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a bottom plan view thereof, with a portion of the broken line drawings removed.

The broken lines in the FIGS. are for illustrative purposes only and form no part of the claimed design.
